UNITED STATES PATENT OFFICE.

JOSEPH FRANCIS HANRAHAN, OF DETROIT, MICHIGAN.

REFRIGERATOR.

SPECIFICATION forming part of Letters Patent No. 432,134, dated July 15, 1890.

Application filed February 6, 1890. Serial No. 339,377. (No model.)

To all whom it may concern:

Be it known that I, JOSEPH FRANCIS HANRAHAN, a subject of the Queen of Great Britain and Ireland, but who has declared his intention of becoming a citizen of the United States, residing at Detroit, in the county of Wayne and State of Michigan, have invented certain new and useful Improvements in Refrigerators, of which the following is a specification.

My invention relates to refrigerators and storage-chambers designed for the preservation of perishable matters; and it consists, primarily, in constructing the same with a partition or division-wall separating the ice-chamber from the storage-chamber, which partition is capable of movement, in whole or in part, as hereinafter explained, to permit the removal of the rack upon which the ice is sustained.

The invention further consists in other features and details of construction, hereinafter set forth, whereby I am enabled to more perfectly regulate and control the direction of the air-currents and their consequent cooling effect.

In the accompanying drawings, Figure 1 is a perspective view of a domestic refrigerator constructed in accordance with my invention; Fig. 2, a vertical section through the same in the direction of the length of the structure; Fig. 3, a vertical section through the same at right angles to Fig. 2; Fig. 4, a horizontal sectional view of the same; Fig. 5, a vertical sectional view illustrating my invention as applied to a refrigerating or preserving room; and Fig. 6, a vertical sectional view illustrating a modification of my invention; Fig. 7, a perspective view of the ice rack or support.

The present invention is the result of certain difficulties encountered in the practical construction and use of this class of refrigerators, it being found in practice that the sediment and impurities contained in ice will in time accumulate upon the ice rack or holder at the bottom of the ice-chamber in sufficient quantity to befoul the chamber and interfere with the perfect action of the apparatus.

Owing to the depth of the ice-chamber and the small size of the door opening into the same, which experience has shown to be advisable in domestic refrigerators and to simi-

lar conditions as to larger structures, it has been found impracticable or exceedingly inconvenient to remove the ice-rack for the purpose of cleaning the same, and the present invention is designed to enable the user to readily remove said rack and to clean out the space beneath the same without changing in any manner the general proportions or arrangement of the structure. With this object in view I construct the apparatus as represented in the annexed drawings, in which—

A indicates the structure as a whole, comprising an ice-chamber B and a storage-chamber C, each extending vertically from top to bottom of the structure, or of that portion of the structure in which each is located. The chambers B and C are separated by a partition D, which under the present construction is made adjustable or movable in such manner that space shall be afforded beneath its lower edge to permit the ice-rack E to be moved laterally into the storage-chamber C, and thence through the opening in the front of the latter chamber whenever desired.

In Figs. 1, 2, 3, and 4 I have represented the partition D as arranged to slide vertically between cleats or guides a, and I have represented said partition as provided with a locking button or block F to enter a notch or recess upon a lug or shoulder b to retain the partition in its elevated position when necessary.

As best shown in Fig. 4, the walls of the ice-chamber B are provided with ribs, cleats, or strips c, whereby shallow channels or passages d are formed in said walls, which will remain open to the passage of air when the chamber is fully supplied with ice, the ice being held away from the walls proper by the ribs or cleats c. These cleats may be applied to all of the walls or to one or more thereof, as deemed best, it being found advisable to apply the same to the partition-wall D, whether used upon the other wall or not. By this construction a downward passage is afforded for the air by the sides of the column or body of ice in the chamber B, as well as through the openings or spaces between the blocks of ice.

G indicates a valve or leaf applied to the lower end of the partition D, and capable of movement in relation thereto to vary the height of its lower edge. The purpose of this

valve is to cause the cold air to descend to a greater or less depth and to compel it to pass below the horizontal partition of the ice-rack and to the bottom of the storage-chamber, or 5 to permit it to pass into the storage-chamber at a higher point, according to the intensity of the cold desired.

In practice it is found that different substances require or may be most advantageously subjected to different degrees of temperature, and this provision enables me to secure the desired variation. It is obvious that instead of being hinged the valve or leaf G may be arranged to slide vertically upon the 15 partition D, suitable ways or guides being provided for it.

As indicated in Figs. 2, 3, and 5, a space is left between the upper end of partition D and the top wall or ceiling of the structure sufficient to allow a free passage of air from the 20 chamber C to the chamber B, the ice-chamber being of the same height as the storage-chamber, or of a greater height if it be desired to place therein a quantity of ice sufficient to 25 last for a long period of time.

The chamber B, being duly supplied with ice, which rests upon the rack E, and the perishable goods being placed within the chamber C, and the doors of the two compartments 30 being closed, the heat contained in said goods is gradually given off to the air of the chamber C, and being warmer than the air of said chamber or of chamber B, it rises to the top of chamber C and passes over the upper edge 35 of partition D into the ice-chamber B, where, being subjected to the colder atmosphere of the latter chamber, it becomes cooled and descends through the chamber D, following the channels d, and also passing through the crevices and interstices of the ice, until it finally 40 passes through the openings of the rack E, and issues out of the bottom beneath the lower edge of partition D and passes again into chamber C.

45 The rack E is of the construction represented in the several figures of the drawings, and consists of end pieces or supports i, which stand at or near the front and back of ice-chamber B, slats j extending from the top of 50 one end support i to the top of the other, and a horizontal diaphragm or partition O at such height that when the valve G is closed it shall meet the horizontal partition and prevent the cold air from passing out above said partition 55 into the storage-chamber C, but compel it to pass to the rear and the ends of the horizontal partition and beneath the same before it can enter said chamber C. When, however, the valve G is opened, the cold air will be permitted 60 to pass directly into chamber C above the partition O. This provision enables me to regulate the degree of cold produced and the travel of the air through the chambers, and is found in practice to be quite important.

In the drawings I have represented the end supports i of the ice-rack as cut away or

shouldered to form a rest or support for the lower end of partition D—a construction which is found convenient, but is not essential.

70 It is a well-known fact that damp air will and that dry air will not hold noxious gases and odors, and the practical use of refrigerators and storage-chambers embodying the construction herein set forth has demonstrated the fact that in passing through and around the ice the moisture contained in the air entering the ice-chamber is condensed and precipitated, passing off through a suitable outlet H at the bottom of the structure, and 80 in this way the air is not only cooled, but it is also purified and deprived of the noxious gases and odors with which it may have become charged while in the storage-chamber. This action going on continuously eventually 85 purifies the contained air of the structure and insures the preservation of the contents of the storage-chamber in a perfectly fresh, pure, and sweet condition.

90 In large structures, owing to the size and weight of the partition D, it may be necessary in some cases to counterbalance the same in whole or in part, which may be done in the manner represented in Fig. 5. In said figure, I indicates a rope or chain, one end of which 95 is attached to the upper end of the partition D, the rope or chain passing thence over pulleys e and f, and being provided at its opposite end with a weight J, which shall nearly or quite counterbalance the weight of the 100 partition D. In said Fig. 5 I have also represented the ice-chamber B as of greater height than the storage-chamber C, and have shown therein the sub-ceiling K, the inclined passage L, and the valve M, set forth in former patents. A catch or locking device F may be employed to hold the partition in its elevated position and prevent accidental descent, as indicated in Fig. 5.

105 Under ordinary circumstances I prefer to employ in the storage-chamber C a grating N, consisting of longitudinal supports g and transverse strips h, whereby the air entering chamber C from chamber B is caused to pass beneath the contents of the storage-chamber 110 and is more evenly diffused over said chamber than would be the case were the rack omitted. For small structures this is not essential, but in larger structures it is quite important.

115 In Fig. 6 I have represented the partition D as having, in addition to the valve G, its lower end or section hinged to the body and adapted to swing upward out of the way of the ice-rack E, so that it shall be unnecessary 120 to lift the partition D as a whole, the space afforded by the raising of the hinged lower section D being sufficient to permit the removal of the ice-rack.

125 It is manifest that the precise construction and arrangement of the partition D is immaterial, provided only that it be so arranged as to permit the enlargement of the opening connecting the lower portions of the cham-

bers B and C to an extent sufficient to permit the passage of the rack E from one chamber to the other.

Having thus described my invention, what 5 I claim is—

1. In a refrigerator or preserving structure, the combination of a chamber, an ice rack or support contained in said chamber, and a partition dividing said chamber into two compartments, said partition being so constructed, substantially as described, as to be movable at its lower end to permit the passage of the ice-rack beneath the partition from one compartment into the other.
- 15 2. In a refrigerator or like structure, a vertically-movable partition dividing the structure into two chambers, and a movable ice-rack located on one side of said partition and adapted, when the movable partition is thrown 20 out of its normal position, to be passed to the other side thereof.
- 25 3. In a refrigerator or like structure, a counterbalanced partition separating the structure into two compartments or chambers, and a movable ice-rack located in one of said chambers and adapted to be moved into the other chamber across the line of the partition when 30 said partition is moved from its normal position.
- 30 4. In a refrigerator or like structure, the combination of ice-chamber B, storage-cham-

ber C, and intermediate movable partition D, provided at its lower end with valve or leaf G.

5. In a refrigerator or like structure, a vertically-movable partition D, provided with a locking device or button F, adapted to engage with a fixed shoulder to hold the partition in an elevated position, and a movable ice-rack E, located on one side of said partition and adapted to be shifted to the other 40 side when the partition is in its elevated position.

6. In combination with ice-chamber B and storage-chamber C, an intermediate partition provided with a valve G, and an ice-rack located in the ice-chamber and provided with open ice-support at the top and with a horizontal partition between said support and the bottom of the ice-chamber.

7. In combination with ice-chamber B and storage-chamber C, intermediate movable partition D, provided with valve G, ice-rack E, located in chamber B and consisting of end supports i, slats j, and horizontal partition O, the end pieces extending under and serving 55 to support the partition D.

In witness whereof I hereunto set my hand in the presence of two witnesses.

JOSEPH FRANCIS HANRAHAN.
